UNITED STATES PATENT OFFICE

EARL C. MEIER, OF WICHITA, KANSAS, ASSIGNOR TO THE PRODUCTION EQUIPMENT COMPANY, OF WICHITA, KANSAS, A CORPORATION OF KANSAS

SUCKER-ROD GUIDE

Application filed January 8, 1929. Serial No. 331,040.

This invention relates to pump rod guides, the primary object being to provide a guide for pump rods or sucker rods used in deep wells such as oil wells, the guide being effective in preventing the sucker rods from whipping and thereby parting.

It is well known that in the oil fields, the sucker rods made up of a plurality of lengths or sections frequently break due to the whipping action caused by the length of the string of rods and the back-lash caused by the change or movement at the end of each stroke. When the string of rods breaks, the well must be shut down for repairs. This interrupts the production of the well. By providing guides at suitable intervals on the string and of approximately the diameter of the tubing, the whipping action is prevented with the result that the pump is maintained in constant operation over a longer period than is possible without the guides. Prior to my invention, guides have been employed but difficulty has been encountered in keeping the guides in position on the rods so my invention relates particularly to a lock or fastening means for holding the guides in fixed positions on the string.

The novelty of the invention will be apparent by reference to the following description in connection with the accompanying drawings in which:

Fig. 1 is a perspective view of a rod guide with the parts in open position ready to be applied to the rod.

Fig. 2 is a perspective view of a rod guide applied and

Fig. 3 is a detailed view of the guide rod lock.

The rod guide proper is shown as consisting of a plurality of cylindrical bushings 1 and 2 having oppositely disposed rod receiving slots 3 and 4 and longitudinal grooves or slots 5 and 6 on their outer portions, the groove 5, when the members 1 and 2 are in place, registering with the slot 4 and the groove 6 registering with the slot 3 so that passageways are provided for the oil or liquid to pass up through the tubing. The members 1 and 2 are pivotally supported on a longitudinal spring rod 7 carrying at its re-

spective ends the locks 8 and 9. The locks 8 and 9 each consists of a substantially U-shaped malleable casting, each having an inclined outer face 10. That is, the outer face of each lock is slightly at a transverse angle and each member 8 and 9 is secured to the end of the rod by a head 11 on the rod. The members 1 and 2 can be swung in opposite directions to open up a space to receive the rod 12 in the slots 3 and 4 as shown in Figure 1. Then the members 1 and 2 are swung around or closed in on the rod as shown in Figure 2. The side edges 13 and 14 of the members 8 and 9 are substantially parallel so that they can swing into rod engaging position so that the rod is received in the recess 15. The ends 16 and 17 of the members 8 and 9 are now brought together to partially close around the rod so that the curved end 18 snugly fits against the rod. In applying the members 8 and 9 about the rod so that the face 10 of each member lies upon the truncated end portions 19 and 20 of the members 1 and 2, the pivot rod 7 is slightly flexed when the guide members 1 and 2 press against the inner faces of the locks 8 and 9 because it is made of spring steel. This causes the major portion of the edge of the slot in the member 8 and in the member 9 to bind on the rod to prevent slipping of the guide.

The member 8 and the member 9 are preferably constructed of a bronze alloy and the members 1 and 2 are constructed of a tough material which will not splinter or shatter, such as bakelite. I have found in actual practice that where wood is used for constructing the members 1 and 2 that the wood shatters and splits and that it gets into the valves of the pump with resultant disadvantages but by employing bakelite, formica, celeron or similar material, the parts wear without clogging up the valves of the pump so I recommend this material as an important part of the invention.

With a device constructed in accordance with my invention, the rod guide will be held in its fixed position for an indefinite period of time. It cannot be jarred loose and the disadvantages present in rod guides in which wood is used is entirely eliminated. It is to

be understood, of course, that the guides are of slightly less diameter than the tubing in which they work so some oil could flow past the guides, but by providing grooves 5 and 5 6 in line with the slots 4 and 3 respectively, relief passage-ways are provided which will permit of adequate flow of the oil through the tubing to the top of the well.

What I claim and desire to secure by Letters Patent is:—

1. A rod guide for oil wells comprising an elongated pivot rod, a plurality of cylindrical rod guide members having rod receiving grooves, said members being independently pivoted eccentrically on the pivot rod and locking members comprising malleable U-shaped castings pivoted on the ends of the pivot rod, the U-shaped members receiving a pump rod, the inner faces of the U-shaped members bearing against the ends of the first 20 named members to flex the pivot rod to cause the inner edges of the U-shaped members to bind against the pump rod.

2. A rod guide for oil wells comprising a 25 plurality of members having rod receiving slots, a pivot rod having inherent flexibility, malleable locking elements carried by the ends of the pivot rod provided with pump rod receiving open slots and having their 30 inner faces adjacent to the pump rod receiving members bearing against the first named members, the open ends of the slots being contractable about the pump rod.

3. A rod guide for oil wells comprising rod 35 receiving members having rod receiving slots, a pivot rod extending through the rod receiving members provided with extended ends, malleable locking members on the extended ends of the pivot rod having open 40 rod receiving slots, the ends of the slots being contractable about the rod to be guided.

In testimony whereof I affix my signature.
EARL C. MEIER.
